UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

LOWER-THREAD MECHANISM FOR CHAIN-STITCH SEWING-MACHINES.

1,257,464.

Specification of Letters Patent. Patented Feb. 26, 1918.

Application filed December 18, 1914. Serial No. 877,861.

To all whom it may concern:

Be it known that I, ALBERT H. DE VOE, a citizen of the United States, residing at Westfield, in the county of Union and State 5 of New Jersey, have invented certain new and useful Improvements in Lower-Thread Mechanism for Chain-Stitch Sewing-Machines, of which the following is a specification, reference being had therein to the accompanying drawings.

This invention has for its object to provide simple and effective means for imparting to a looper from a single actuating element movements both endwise and crosswise 15 of its blade in coöperation with a reciprocating needle for the production of stitches.

In the preferred embodiment of the invention, the looper is mounted for endwise and sidewise movements upon a carrier mounted 20 to oscillate upon and slide endwise of a suitable support and having an operative connection with an actuating crank inclined to, and embraced within a plane parallel with, the axis of motion upon which it turns, said 25 crank being adapted to impart to the looper both of its angularly related motions.

The invention also includes, in conjunction with said looper-actuating means, a lower thread take-up device comprising a 30 rock-shaft carrying vibratory take-up arms and provided with a crank-arm having a toggle connection with an intermediate rock-shaft deriving operative movements from a crank or eccentric upon the main-shaft. 35 The operation of the take-up device is such that slack thread is rapidly given up to the loopers in their advance to extreme forward position and taken up with corresponding rapidity in the initial retraction of the loopers, while the dwell and slight reverse movement of the take-up arms in the retracted 40 positions of the loopers serve to insure the proper control of the lower threads as the loopers are about to seize upper thread loops 45 from the needles.

The invention will be understood by reference to the accompanying drawings, in which Figure 1 is a front elevation and Fig. 2 a plan of a portion of a two-line sewing 50 machine embodying the present improvements, and Fig. 3 is an end elevation of the same, partly in section. Fig. 4 is an elevation, and Fig. 5 a plan of the loopers and their actuating means.

55 As represented in the drawings, the ma-

chine frame is provided with the bed 1 from which rise the bearing members 2 and 3, in which is journaled the rotary shaft 4 disposed lengthwise of the bed. The shaft is formed intermediate said bearings with the 60 spaced and offset disks 5 and 6 which sustain between them the crank-pin 7 which is shown disposed at a slight inclination with the adjacent portions of the shaft 4 but axially within a plane parallel with and 65 spaced from the axis of the shaft.

The crank-pin 7 is embraced by a crank-follower in the form of a sleeve comprising the body portion 8 and cap 9 each provided with complementary parts of the end flanges 70 10 and 11, the body portion 8 of the sleeve, having depending therefrom the laterally inclined arm 12 formed at its lower end with a ball-socket closed by the cap 13.

The socket of the arm 12 embraces the 75 head 14 of a bell-stud whose shank is secured by means of the set-screw 15 within a socket of a short lateral crank-arm 16 of the looper-carrier 17. The sleeve 8, 9, and the depending arm 12 will be seen to constitute 80 a pitman connection between the crank-pin 7 and the looper-carrier 17. It is to be understood, however, that the pitman need not necessarily be directly connected to the looper-carrier or a part rigidly connected 85 thereto, although a direct connection such as illustrated is preferred. The looper-carrier is formed with a transverse sleeve-like hub portion 18 which is slidingly mounted upon the eccentric bearing portion 19 of a pivotal 90 pin formed at one end with the reduced portion 20 entering a suitable bearing aperture of the bed-plate bearing member 2 and at the opposite end an enlarged portion 21 similarly journaled within an aperture of 95 the bearing member 3, the portion 22 beyond the enlarged portion 21 having fixed thereon the crank 23 adapted to be manually operated to shift the pivotal pin laterally, as described more particularly in my pending 100 application Serial No. 793,535, filed October 6, 1913, which discloses a looper mechanism of which the present construction is a modification.

The looper-carrier has at its upper end a 105 transverse head 24 having sockets to receive the depending pins 25 of the blocks 26 to which are secured by means of screws 27 the shanks 28 of the looper-blades 29. The looper-blades are provided adjacent their 110

points with the thread-apertures 30 leading to which are the usual lateral grooves 31 for the thread passing through the guide-eyes 32 at the heels of the loopers.

5 In the rotation of the shaft 4, the crank-pin 7 is carried in a path which is practically cylindrical and concentric with the axis of the shaft. This revolving movement of the crank-pin obviously acts through the 10 arm 12 of the sleeve 8 to impart rocking movements to the looper-carrier 17, while the slight lateral inclination of the crank-pin 7 causes the arm 12 to perform a slight vibratory movement which is transmitted 15 through its ball-and-socket connection with the looper-carrier arm 16, thereby imparting to the latter its sidewise sliding movements. The rocking movements of the looper-carrier upon its pivotal support obviously 20 communicates endwise or loop-seizing movements to the loopers, while the lateral sliding movements of the carrier impart to the loopers their usual sidewise movements.

Journalized in a forward extension of the 25 bearing member 3 and in a post 33 at the front of the bed 1 is the take-up rock-shaft 34 which is shown provided with the two thread-pins 35 each provided in its outer end with a thread-eye 36. The shaft 34 has 30 secured thereon the collar 37 having the crank-arm 38 embraced by the forked lower extremity of the link 39 pivoted thereto by means of the pin 40, said link embracing within its opposite forked end and pivotally 35 secured by means of the pin 41 to the depending arm 42 of a collar 43 secured upon one end of the intermediate rock-shaft 44.

The rock-shaft 44 is journaled within a bearing boss 45 of the post 33 and has fixed 40 upon its opposite end the hub 46 of a crank-arm 47 pivotally connected by means of the screw-stud 48 with the apertured boss 49 of the eccentric rod 50 provided with the strap 51 embracing the actuating eccentric 45 52 fixed upon the main-shaft 4. The swinging movements of the crank-arm 42 are such as to carry the link 39 into and out of alignment with itself, so as to produce a toggle movement for imparting a dwell and accelerated operative movements of the crank-arm 38 from which the rock-shaft 34 and thread-arms 35 derive their operative movements.

Rising from the bed 1 is the thread-guide 55 post 53 provided with the thread-eyes 54 through which one of the looper-threads is led to the outer thread-eye 36 of the nearer take-up arm 35 and thence to the corresponding looper 29, while the other is led 60 through a second thread-eye 36' and thence to the eye of the second take-up arm from which it is led to its respective looper.

In the operation of the parts of the mechanism thus far described, in the retracted 65 positions of the loopers and while the nee-

dle-thread loops are being set, the looper-thread is slackened, but as the loopers begin their advance to seize new needle-thread loops, the slack is initially taken up by the take-up arms moving slightly backward as 70 the toggle passes straightened position after which both loopers and take-up arms move forwardly, the take-up arms moving more rapidly as the loopers reach their advance positions, so as to give up a supply of the 75 thread leading from the take-up eye to the eye of the loop-taker and backwardly to the work. As the loopers begin their receding movements, and rapidly give up the thread of the loop thus formed, this thread is 80 drawn up by the rapid retraction of the take-up arms so as to maintain the control of the thread into the initial retracted position of the loopers.

The loopers coöperate with the usual eye-pointed needles 55 mounted in the plural needle-carrier 56 upon the reciprocating needle-bar 57.

One of the chief advantages of the looper mechanism herein shown and described is 90 the provision for comparatively large wearing surfaces and few joints between the operative parts involving simplicity in construction, which insures durability and freedom from noise at high speeds. It will be 95 observed that in the present construction this mechanism involves only three pivotal joints, comprising the sleeve of the crank-member 12 embracing the actuating crank 7, the ball-and-socket connection between 100 the same and the looper-carrier, and the journal of the looper-carrier upon the bearing portion 19 of the pivotal pin or support.

The feeding mechanism is or may be constructed in accordance with that of my pending application Serial No. 813,841, filed January 23, 1914, and comprises the usual feed-dog 58 engaging the work through an aperture 59 in the throat-plate 60. Opposed to the feed-dog is the presser-foot 61 whose shank 62 is secured to the reduced lower extremity of the presser-bar 63.

Having thus set forth the nature of the invention, what I claim herein is:—

1. In a sewing machine, in combination, a 115 looper, a carrier therefor, a support upon which said looper-carrier is mounted for sidewise and endwise movement, an actuating shaft provided with a crank having its axis inclined thereto but movable in a substantially cylindrical path concentric therewith, and a pitman connection between said crank and the looper-carrier from which the latter derives both of said movements.

2. In a sewing machine, in combination, 125 an eye-pointed needle, a looper movable endwise to seize a needle-loop and sidewise to position a loop for subsequent entry by the needle, a carrier for said looper, a support upon which said carrier is mounted to slide 130

and to oscillate, an actuating shaft provided with a crank having its axis inclined to, but movable in a substantially cylindrical path concentric with, the axis of said shaft, the 5 axis of said crank being disposed in non-intersecting relation with the axis of said shaft, and a crank-follower embracing said crank and connected to the looper-carrier for imparting to the latter oscillatory and 10 sliding movements, whereby the loop-seizing movements of the said looper are caused to lie mainly in a direction at right angles to the direction of sliding movement of said looper-carrier on said support.

15 3. In a sewing machine, the combination with a reciprocating needle, a work-support, a driving shaft, a thread-carrying looper and operative connections between said shaft and looper for imparting to said looper its 20 loop-seizing and shedding movements, of a take-up comprising a rock-shaft, a crank-arm and a thread-guiding arm carried by said rock-shaft, said thread-guiding arm being disposed adjacent the looper, an intermediate shaft carrying a 25 crank-arm, operative connections between said intermediate shaft and said driving shaft independent of the connection between said driving shaft and looper, and a link connection between 30 said crank-arms adapted to move into and

out of alinement with the crank-arm on said intermediate shaft.

4. In a sewing machine, the combination with a reciprocating needle, a work-support, a driving shaft journaled below the work 35 support, a thread-carrying looper mounted for needle-loop seizing movements transversely of said driving shaft, and operative connections between said shaft and looper, of a take-up comprising a rock-shaft disposed substantially parallel to said driving shaft, a crank-arm and a thread-guiding arm carried by said rock-shaft, said thread-guiding arm being disposed adjacent the looper, an intermediate shaft carrying a 40 crank-arm, operative connections between said intermediate shaft and said driving shaft independent of the connections between said driving shaft and looper, and a link connection between said crank-arms 45 50 adapted to move into and out of alinement with the crank-arm on said intermediate shaft.

In testimony whereof I have signed my name to this specification in the presence of 55 two subscribing witnesses.

ALBERT H. DE VOE.
